(57) **CLAIM**

The ornamental design for a ballistic shield, as shown and described.

DESCRIPTION

FIG. 1 is a front, right side perspective view of a ballistic shield showing my new design;

FIG. 2 is a front view thereof;

FIG. 3 is a rear view thereof;

FIG. 4 is a left side view thereof, the right side view being a mirror image thereof;

FIG. 5 is a top view thereof;

FIG. 6 is a bottom view thereof; and,

FIG. 7 is a front view of an arrangement of a plurality of the ballistic shield shown in FIGS. 1-6.

The broken lines shown in FIG. 7 shows unclaimed environment and forms no part of the claimed design.
